FIG. 1

FIG. 2

FIG. 3

INVENTOR
A. C. MUDGE
By J. G. Cook
ATTORNEY

UNITED STATES PATENT OFFICE

ARCHIBALD C. MUDGE, OF ST. LOUIS, MISSOURI, ASSIGNOR TO BROWN SHOE COMPANY, INC., OF ST. LOUIS, MISSOURI, A CORPORATION OF NEW YORK

SHOE

Application filed May 22, 1929. Serial No. 364,969.

This invention relates generally to shoes, and more specifically to improved shoes which are so constructed as to permit of same being arranged on or removed from the feet of wearers of said shoes without untying the laces thereof, the predominant object of the invention being to produce shoes of the character mentioned which will be neat in appearance and comfortable to the wearer when in use.

Fig. 1 is a plan view of a shoe constructed in accordance with this invention.

Fig. 2 is a side elevation of the shoe shown in Fig. 1.

Fig. 3 is a view similar to Fig. 1 but showing the shoe as same will appear when same is to be placed on or removed from a person's foot.

In the drawing, wherein is shown, for the purpose of illustration merely, one embodiment of the invention, A designates my improved shoe, which includes the usual upper B, outsole C, and heel D. The shoe A, except for the forepart of the upper thereof, is constructed in the ordinary and well known manner, and it is with respect to the construction of the shoe at the forepart of the upper B that this invention relates.

By referring to Fig. 3 of the drawing, it will be noted that the edges 1 of the upper B at the forepart of the shoe A are permanently spaced apart from each other to provide a space 2 between said edges 1, which space is of substantially constant width from top to bottom, the bottom of said space being located at the instep of the shoe and the upper end thereof at the top of the upper of the shoe. The portions of the shoe upper adjacent to the edges 1 in the ordinary lace shoe are drawn together by the laces, but in the case of my improved shoe no laces are associated directly with these shoe portions. 3 designates the tongue of the shoe A which is secured to the shoe, preferably only at the bottom edge of said tongue.

Secured to the shoe A at the instep thereof is a pair of flaps 4 and 5, which are disposed at the forepart of the upper of the shoe. The flaps 4 and 5 are secured at their lower ends to the shoe by means of the rows of stitches

6 which serve at the sides of the shoe to secure the upper to the vamp of the shoe. At their upper ends the flaps 4 and 5 are flared outwardly as illustrated clearly in Figs. 1 and 3, and each of said flaps is provided with a plurality of recessed elements 7 constituting parts of fastening devices. Secured to the upper of the shoe at points adjacent to the edges 1 thereof is a plurality of fastener parts 8, which include projections adapted to be inserted into the recesses in the fastener parts 7 fixed to the flaps. The fastening devices produced by the fastener parts 7 and 8 resemble the ordinary glove fastener, and with the aid of said fastening devices the upper flared portions of the flaps 4 and 5 may be securely attached to the shoe upper at the forepart of the shoe.

Adjacent to the inner edges of the flaps 4 and 5 said flaps are provided with rows of apertures 9 through which a shoe lace 10 may be passed in the usual manner for the purpose of lacing the inner edge portions of the flaps together, as shown clearly in Figs. 1 and 3, said shoe lace being tied in a bow at the upper ends of the flaps, as is ordinarily the case with shoe laces.

When the flaps 4 and 5 of a shoe constructed in accordance with this invention are secured to the upper of the shoe by means of the fastening devices referred to, the shoe has the appearance of an ordinary lace shoe. It is obvious, of course, that the flaps 4 and 5 are visible, but these flaps do not detract from the appearance of the shoe but, instead, serve to add a decorative touch thereto. When it is desired to put on or remove my improved shoe from the foot it is not necessary to untie the laces 10, as is ordinarily the case, all that is necessary being for the fastening devices by which the flaps 4 and 5 are secured to the shoe upper to be unclasped, whereby the forepart of the shoe upper will be open to permit ready and convenient application to or removal from the wearer's foot.

In view of this arrangement the shoe laces may remain neatly tied at all times, and because said laces need not be untied each time the shoe is put on or removed from the

wearer's foot, much time is saved during such operations.

I claim:

1. A shoe including an upper, flaps fixed permanently to the shoe at the forepart of said upper, means for detachably securing portions of said flaps to said upper, and means for lacing said flaps together.
2. A shoe including an upper, flaps fixed permanently to the shoe at the forepart of said upper, means comprising friction fastening devices, cooperable parts of which are associated with said shoe upper and said flaps, for detachably securing portions of said flaps to said upper, and means for lacing said flaps together.
3. A shoe including an upper, flaps at the forepart of said upper, said flaps being secured at their lower ends to said shoe, means for detachably securing said flaps to said upper, and means for lacing said flaps together.

In testimony that I claim the foregoing I hereunto affix my signature.
